UNITED STATES PATENT OFFICE.

WALTER S. COE, OF BROOKLYN, NEW YORK, ASSIGNOR TO MERGENTHALER LINOTYPE COMPANY, A CORPORATION OF NEW YORK.

TYPE OR MATRIX.

1,151,567.

Specification of Letters Patent. Patented Aug. 31, 1915.

Application filed September 22, 1914. Serial No. 862,934.

To all whom it may concern:

Be it known that I, WALTER S. COE, a citizen of the United States, residing at Brooklyn, in the county of Kings and State of New York, have invented certain new and useful Improvements in Type or Matrices, of which the following is a specification, reference being had therein to the accompanying drawing.

10 My invention relates to the type or matrices used in typographical machines, such for instance as that disclosed in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal to form a 20 slug or linotype against the matrices which produce the type characters thereon, and the matrices thereafter returned through distributing mechanism to the magazine from which they started.

25 More particularly, it relates to a form of matrix, the body of which is recessed or cut away to lighten or reduce its weight, but which is nevertheless formed with a solid and unbroken bottom edge to facilitate its 30 coöperation with the operative parts of the machine, such for instance as the distributor box lift. This construction obviates an objection present in the lightened matrices now in general use, such as those appertaining to the "Model 9" linotype, wherein the reducing or lightening grooves cut away the bottom of the matrix to such an extent that there is comparatively little continuous surface remaining for the lift to act upon.

35 In the accompanying drawing, I have shown my invention in a variety of forms and as applied to linotype matrices, but obviously many changes and variations may be made therein, and in its mode of application, which will still be comprised within its spirit. Similarly, it may be adapted to type or dies as well as to matrices. Generally speaking, I desire it to be understood that I do not limit myself to any specific 45 form or embodiment, except in so far as such limitations are specified in the claims.

40 Referring to the drawing: Figures 1 and 1^a are respectively perspective and transverse sectional views of the improved ma-

trix; Figs. 2 and 2^a are a perspective and a 55 longitudinal section of a modified form; Figs. 3 and 3^a are a perspective and a transverse section of still another form; and Figs. 4 and 4^a are a side elevation, partly broken away, and a transverse section of a fourth 60 form.

Referring to Figs. 1 and 1^a, the matrix X is lightened or reduced in weight by the recesses or cuts A formed in its side, and separated by the intermediate wall B. It will 65 be noted that these recesses terminate above the bottom edge of the matrix, and thus leave the latter solid and uninterrupted to facilitate its coöperation with the operative elements of the machine, such as the dis- 70 tributer lift.

In Figs. 2 and 2^a, the matrix X¹ is similarly formed with cuts or recesses A¹ and the intermediate wall B¹, but the recesses pass entirely through the matrix from one 75 side to the other.

In Figs. 3 and 3^a, the matrix X² is formed with reducing or lightening recesses A² in one side, the recesses being in the form of cylindrical holes or bores.

In Figs. 4 and 4^a, the matrix X³ is formed with longitudinal or vertical bores or holes A³.

80 In all of the several embodiments illustrated, the recesses or cuts terminate above the bottom edge of the matrix and leave the latter solid and uninterrupted for the reasons and purposes before outlined.

85 As previously stated, I have shown my invention only in preferred form and by way of example, and in special modes of adaptation. However, many modifications and alterations therein, and in the mode of application, will suggest themselves to those skilled in the art, without departure from 90 its scope.

95 Having thus described my invention, its construction and mode of operation, what I claim and desire to secure by Letters Patent of the United States, is as follows:

100 1. A type or matrix provided with a distributing combination, and comprising a recessed body portion whose bottom edge is unaffected by the recessing, for the purpose described.

105 2. A type or matrix provided with a distributing combination, and formed with a lightening recess in its side face, the said

recess terminating above the bottom edge of the type or matrix so as to leave said edge intact, for the purpose described.

3. A type or matrix provided with a distributing combination, and formed in its side face with a longitudinal groove terminating above its bottom edge so as to leave said edge intact, for the purpose described.

4. A type or matrix provided with a distributing combination, and formed in its side face with the two lightening grooves A

leaving the intermediate wall B, the said grooves terminating above the bottom edge of the type or matrix so as to leave said edge intact, for the purpose described.

In testimony whereof, I have affixed my signature in presence of two witnesses.

WALTER S. COE.
